CONTAINER RING

Rolf E. Ljungkull, St. Paul, Minn., assignor to
 American Hoist and Derrick Company, St.
 Paul, Minn., a corporation of Delaware

Application December 3, 1934, Serial No. 755,735

22 Claims. (Cl. 308—235)

This application is a continuation in part of my pending application Serial No. 721,983, for Excavating machines, filed April 23, 1934.

The invention relates to a container ring of the character including rollers or wheels adapted to ride a lower rail upon a supporting structure of an excavating or like machine and to be engaged by an upper rail carried by a platform revolvably mounted upon said supporting structure. That is to say, the container ring of the present invention is adapted to the purpose of supporting, or assisting in the support of, a revolvable platform, as, for example, of an excavating machine, upon a supporting structure for said platform.

The object of the invention is to provide a container ring, having rollers or wheels adapted to ride a lower rail, as on a supporting structure, and support an upper rail, as on a revolvable platform, in which will be incorporated novel and improved features of construction.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawing forming a part of this specification,—

Fig. 1 is a plan view of a container ring made according to the invention;

Fig. 2 is an enlarged fragmentary view, partially in plan and partially in horizontal section; and

Fig. 3 is a fragmentary elevational view.

With respect to the drawing and the numerals of reference thereon, the container ring consists of inner and outer continuous, annular bands, denoted 10 and 11, respectively, supporting rollers or wheels 12 adapted to engage a lower rail, as on a supporting structure, and to be engaged by an upper rail, as on a revolvable platform.

The rollers or wheels 12 are freely rotatable on shafts 13 mounted in said inner and outer bands 10 and 11, in a manner to be described, at equally spaced distances apart about the full circumference of the container ring.

Each of the bands 10 and 11 could consist of a single circular strip or piece of metal. As

disclosed, however, each band consists of several arcuate strips or pieces of metal, denoted 14, having their adjacent end portions connected together by plates 15 and headed and nutted bolts 16. The connecting plates 15 for the arcuate strips or pieces 14 of the inner band 10 are at the inner side of the container ring, and the connecting plates 15 for the arcuate strips or pieces 14 of the outer band 11 are at the outer side of said container ring. Said connecting plates have their opposite end portions arranged in contiguous, overlapping relation to adjacent end portions of the arcuate strips or pieces of the bands, and each bolt 16 passes through a plate and a strip or piece, the heads and nuts 15 on the bolts serving to clamp the plates and the strips or pieces against each other. The plates 15 are arcuate in the direction of their lengths to fit the arcuate strips or pieces.

The continuous bands 10 and 11 are held in 20 suitably spaced apart relation by headed and nutted bolts 17 passing through said bands, and tubular spacers or pipe separators 18 upon said bolts 17 and between the inner and outer bands. There are desirably as many units each consisting of a headed and nutted bolt 17 and a spacer or separator 18 as there are rollers or wheels 12, and said units are at equally spaced distances apart about the container ring, there being a unit 17, 18 midway between each of adjacent 25 rollers or wheels 12. The opposite ends of each tubular spacer or pipe separator engage the interior surfaces of the inner and outer bands, respectively, or, in other words, the outer surface of the inner band and the inner surface of 30 the outer band. The head and nut on each bolt 17 engage the exterior surfaces of said inner and outer bands, or, in other words, the inner surface of the inner band and the outer surface of 35 the outer band, to clamp the bands against the spacers or separators and thus fix the relation of said bands to each other.

The shafts 13 for the different rollers or wheels 12 assist in retaining the bands 10 and 11 in fixed relation. Each shaft has its outer end portion 45 welded, as at 19, to a plate 20. The shafts pass, desirably snugly, through openings 21 in the outer band 11, and the plates 20 are secured to said outer band by headed and nutted bolts 22, one at either side of each shaft. The bolts 22 50 pass through the plates 20 and the band 11, and the heads and nuts on the bolts clamp said plates 20 against the outer surface of the outer band. The plates 20 are arcuate in the direction of their lengths to fit the outer band. A washer 23 is 55

situated upon each shaft 13 between the inner surface of the outer band and the corresponding roller or wheel 12. Each shaft 13 includes a reduced threaded portion 24 at the inner end of the shaft which passes through the inner band and provides a circumferential shoulder 25 adjacent the interior or outer surface of said inner band. A nut 26 upon each threaded portion 24 is turned home against the exterior or inner surface of the inner band, to force said band against the corresponding shoulder 25. The rollers or wheels 12 are desirably of width to about span the distance between the inner band 10 and the washers 23.

15 The container ring supports the rollers or wheels 12 in a circumference having diameter equal to that of the circumference described by upper and lower rails in connection with which the container ring is to be employed, and the 20 traveling surface of each roller or wheel may be grooved, as indicated at 27, to fit upper and lower rails.

What is claimed is:

1. In a container ring, spaced apart inner and 25 outer arcuate members, a roller between said arcuate members, a shaft mounted on said inner and outer arcuate members and carrying said roller, a plate welded to one end portion of said shaft and clamped to an arcuate member, 30 and means at the other end portion of said shaft for fastening the shaft to the other arcuate member.

2. In a container ring, spaced apart inner and 35 outer arcuate members, a roller between said arcuate members, a shaft mounted on said inner and outer arcuate members and removably carrying said roller, a plate welded to one end portion of said shaft and bolted to an arcuate member, and a nut on the other end portion of said shaft for 40 clamping the other arcuate member to the shaft.

3. In a container ring, spaced apart inner and 45 outer arcuate members, a roller between said arcuate members, a shaft mounted on said inner and outer arcuate members and removably carrying said roller, a plate welded to said shaft and bolted to one of the arcuate members, a reduced portion at the end of said shaft spaced from said plate and mounted in the other arcuate member, said reduced portion providing a shoulder 50 upon said shaft adjacent said other arcuate member, and a nut upon said reduced portion for clamping said other arcuate member against said shoulder.

4. In a container ring, spaced apart inner and 55 outer arcuate members, a roller between said arcuate members, a shaft mounted on said inner and outer arcuate members and carrying said roller, a plate welded to said shaft and surrounding an end portion thereof, bolts for clamping 60 said plate against a surface of one of said arcuate members to fix the relation of said shaft and arcuate member relatively to each other, a reduced and threaded portion at the end of said shaft spaced from said plate, said reduced portion being mounted in the other arcuate member and providing a shoulder upon said shaft adjacent said other arcuate member, and a nut upon said threaded portion and engaging 65 a surface of said other arcuate member to clamp it against said shoulder and fix the relation of said shaft and other arcuate member relatively to each other.

5. In a container ring, spaced apart inner and 70 outer arcuate members, a roller between said arcuate members, a shaft for said roller, a plate

welded about said shaft and bolted to one of said arcuate members, a reduced and threaded portion at the end of said shaft spaced from said plate, said reduced portion being mounted in the other arcuate member and providing a shoulder upon said shaft, and a nut upon said threaded portion for clamping said other arcuate member against said shoulder. 5

6. A container ring comprising spaced apart inner and outer annular members, spaced apart 10 rollers between said annular members, a shaft removably carrying each roller mounted on said inner and outer annular members, means for detachably fastening each shaft in fixed relation to said inner and outer annular members, spacers 15 between said inner and outer annular members, and means for detachably clamping said inner and outer annular members against said spacers.

7. A container ring comprising spaced apart inner and outer annular members, spaced apart 20 rollers between said annular members, a shaft for each roller mounted on said inner and outer annular members, means for fastening said shafts and inner and outer annular members in fixed 25 relation to each other, and spacing units for said inner and outer annular members between adjacent rollers, each of said spacing units consisting of a tubular spacer between the inner and outer annular members, and a headed and nutted bolt passing through said tubular spacer and 30 said inner and outer annular members and clamping the members against the opposite ends of the tubular spacer.

8. The combination as specified in claim 6, 35 wherein each of said inner and outer annular members consists of separate arcuate strips of metal, and metal plates connecting said strips to each other, said metal plates overlapping adjacent end portions of the strips and being bolted thereto. 40

9. A container ring comprising spaced apart inner and outer annular members, spaced apart 45 rollers between said annular members, shafts mounted on said inner and outer annular members and carrying said rollers, and spacing units 50 for said inner and outer annular members between adjacent rollers, each of said spacing units consisting of a tubular spacer between the inner and outer annular members, and a headed and nutted bolt passing through said tubular spacer and said inner and outer annular members and clamping the members against the ends of the tubular spacer. 55

10. In a container ring, spaced apart inner and 60 outer arcuate members, a roller between said arcuate members, a shaft removably mounted on said inner and outer arcuate members and removably carrying said roller, a plate fastened to one end portion of said shaft and to an arcuate member, and means at the other end portion of 65 said shaft for detachably fastening the shaft to the other arcuate member. 60

11. In a container ring, spaced apart inner and 65 outer arcuate members, a roller between said arcuate members, a shaft removably mounted on said inner and outer arcuate members and removably carrying said roller, a plate fastened to one end portion of said shaft and detachably secured to an arcuate member, and means for detachably securing the other end portion of said shaft to the other arcuate member. 70

12. In a container ring, spaced apart inner and 75 outer arcuate members, a roller between said arcuate members, a shaft removably mounted on said inner and outer arcuate members and re- 75

- movably carrying said roller, a plate carried by said shaft and surrounding an end portion thereof, means for fastening said plate to one of said arcuate members to fix the relation of said shaft 5 and arcuate member relatively to each other, said shaft having its other end portion mounted upon the other arcuate member, and means for fastening said other end portion of the shaft to said other arcuate member.
- 10 13. In a container ring, spaced apart inner and outer arcuate members, a roller between said arcuate members, a shaft removably carrying said roller, a plate about said shaft for detachably securing the shaft to one of said arcuate members, an end portion of said shaft opposite said plate being removably mounted on the other arcuate member, and means for detachably securing said opposite end portion of said shaft to said other arcuate member.
- 15 14. A container ring comprising spaced apart inner and outer annular members, spaced apart rollers between said annular members, a shaft removably carrying each roller removably mounted on said inner and outer annular members, means for detachably fastening each shaft in fixed relation to said inner and outer annular members, means between said inner and outer annular members for spacing them apart, and means for detachably securing said spacing 20 30 means to the annular members.
15. A container ring comprising spaced apart inner and outer annular members, spaced apart rollers between said annular members, a shaft removably carrying each roller and removably 35 mounted on said inner and outer annular members, and spacing units between said inner and outer annular members and detachably secured thereto for fastening the annular members in fixed relation to each other.
- 40 16. In a container ring, spaced apart inner and outer arcuate members, a roller between said arcuate members, a shaft mounted on said inner and outer arcuate members and carrying said roller, means in spaced relation to said shaft for fastening one end portion of the shaft in fixed relation to one of said arcuate members, and means at the other end portion of said shaft for fastening the shaft in fixed relation to the other arcuate member.
- 45 17. In a container ring, spaced apart inner and outer arcuate members, a roller between said arcuate members, a shaft mounted on said inner and outer arcuate members and removably 50 carrying said roller, means in spaced relation to said shaft for detachably fastening one end portion of the shaft in fixed relation to said arcuate member, and means at the other end portion of said shaft for fastening the shaft in fixed relation to the other arcuate member.
- carrying said roller, means in spaced relation to said shaft and engaging an arcuate member for detachably fastening one end portion of the shaft in fixed relation to said arcuate member, and means at the other end portion of said shaft and engaging the other arcuate member for detachably fastening the shaft in fixed relation to said other arcuate member.
18. In a container ring, spaced apart inner and outer arcuate members, a roller between said arcuate members, a shaft mounted on said inner and outer arcuate members and carrying said roller, a plate secured to one end portion of said shaft and removably secured to an arcuate member, and means for mounting the other end portion 10 15 of the shaft upon the other arcuate member.
19. In a device of the character described, spaced apart members, a roller between said members, a shaft mounted on said spaced apart members and carrying said roller, means in spaced relation to said shaft for fastening one end portion of the shaft in fixed relation to one of the members, and means for fastening the shaft in fixed relation to the other member.
20. In a device of the character described, spaced apart members, a roller between said members, a shaft mounted on said spaced apart members and carrying said roller, a plate connected to said shaft and secured to a member, and means for mounting said shaft in the member opposite the one to which said plate is connected.
21. In a device of the character described, spaced apart members, a roller between said members, a shaft mounted on said spaced apart members and carrying said roller, a plate secured to an end portion of said shaft and detachably connected to a member, and means for mounting the other end portion of said shaft in the member opposite the one to which said plate is secured.
22. In a container ring, spaced apart inner and outer arcuate members, a roller between said arcuate members, a shaft removably mounted on said inner and outer arcuate members and carrying said roller, means at opposite sides of and in spaced relation to said shaft for detachably fastening an end portion of the shaft in fixed relation to one of said arcuate members, and means for detachably fastening the other end portion of said shaft in fixed relation to the other arcuate member.

ROLF E. LJUNGKULL.
